MANIFOLDING MACHINE

Filed Nov. 13, 1926

UNITED STATES PATENT OFFICE

WILLIAM G. BOECHERS, OF HOBOKEN, NEW JERSEY, ASSIGNOR TO AUTOGRAPHIC REGISTER COMPANY, OF HOBOKEN, NEW JERSEY, A CORPORATION OF NEW JERSEY

MANIFOLDING MACHINE

Application filed November 13, 1926. Serial No. 148,204.

This invention relates to manifolding machines, and more particularly to machines adapted to store therein a record copy of the work performed on the machine.

With some kinds of paper and under some conditions in record-storing types of manifolding machines, some difficulty has been encountered in properly storing the record copy due to the fact that the record sheet has a tendency to curl and does not lie in the record compartment in a flat condition so that a neat pack is not produced. This tendency of the paper to curl when the paper stands for a considerable time in roll form, is due to the fact that one surface of the paper is stretched more than the other surface with the result that as soon as the worksheet is free to do so it will curl up.

It is an object of this invention to avoid this difficulty, and this is accomplished by providing a longitudinally creased or embossed line in the record copy. It has been found in practice that when the record copy is given one or more creases or embossed ridges it will lie substantially flat in the record compartment. If desired, the record copy may be previously creased before it is placed in the machine, but, according to the present invention, it is preferred to crease or emboss the record copy in the machine while it is being fed or advanced therethrough.

In the accompanying drawing, which illustrates one embodiment of this invention, that at present preferred—

Figure 1 is a side view of a record-storing type of manifolding machine with the sides broken away to show the supply and record-storage compartment and the mechanism of the present invention.

Fig. 2 is a perspective view showing the record sheet creasing means of the present invention.

Fig. 3 is a detail view showing one of the sheet creasers of the present invention and the means with which it cooperates.

As shown in the accompanying drawing, the manifolding machine comprises side plates 10 and a bottom 11 supported on feet 12. The rear part of the machine between

the side plates 10 constitutes a supply compartment for a pack 13 of worksheets which lie on top of the bottom 11, and from the pack 13 the worksheets 14 and 14a are led upwardly over guide rods 15 around which they bend and from which they extend forwardly so as to lie over a platen 16 upon which the worksheets 14 and 14a are supported during writing operations. After a writing operation has been performed, the worksheets are advanced by feed mechanism comprising feed rollers 17 and 17a operated through gearing (not shown) by a crank or handle 18. When all of the worksheets are thus advanced, the worksheets 14 are ejected or fed from the machine at 19 so as to assume the positions shown in dotted lines in Fig. 1, from which position they may be drawn upwardly and rearwardly over a severing knife 20 to be torn from the contiguous parts remaining in the machine and still under the control of the feed mechanism. The record sheets 14a, however, are not ejected but pass downwardly and fall onto a record support 21, one upon the other, to form a stack such as is shown in Fig. 1, as they are severed one after another by a knife (not shown) operated at the conclusion of the feeding operation. On this record support 21, the record copies 14 are held against tampering until access is gained to the record compartment by means of a locked door 22.

As above stated, it is not infrequent that the record copies 14a, due to their tendency to curl, do not fall in a neat pack or pile on the record support 21 and when this occurs it is necessary to rearrange the record sheets 14a after they are taken from the machine. Moreover, occasionally, the record sheets 14a, when so disarranged, pile up in the record compartment so as to interfere with the proper operation of the machine and necessitating the opening of the door 22 and rearrangement of the sheets before the machine can again be operated.

This tendency of the record strip to curl is inherent in the paper and is unavoidable and practically incurable so far as is now known. It is probably caused by the one

surface of the paper being stretched or tensioned for a long period more than the other surface of the paper which may occur when the paper stands for a protracted period in rolled form. It has even been found that rerolling of the paper in the opposite direction and keeping it that way for a substantial period does not overcome this tendency, for no balanced condition can be had, and should the period during which the paper is rerolled exceed the initial rolled period or should the climatic conditions favor it, the paper will be bound to have a tendency to roll in the opposite direction which is almost if not quite as bad as the former conditions. It has also been found that the paper, which has stood in a pack form as shown in Fig. 1, for a considerable time, still has the characteristics of curling as soon as it is free to do so.

The present invention instead of attempting to correct the surface tension of the paper so as to prevent it from curling, overcomes these difficulties referred to by creasing or embossing the sheet longitudinally so as to provide a stiffening rib or ridge making the paper more rigid, and hence neutralizing the tendency to curl.

It has been found in practice that a single crease running longitudinally of the paper at about the center thereof will avoid the difficulty due to curling, but best results have been obtained when the paper is provided with two longitudinal creases, as in the form shown.

It has also been found in practice that the paper may be previously creased as can be done in the press while the paper is being printed, but in such case, of course, the crease is not as effective as it is when made in the machine because the crease is ironed out due to the weight of the paper above it in the pack.

It has been found by experiment that the record sheets 14a may be creased in the immediate vicinity of the feed rollers with good results. However, in the specific type of recording manifolding machine shown, it is preferable to cause the creasing to be performed as the record sheets 14a are being introduced to the platen, for in the type of machine shown, there is provided certain convenient mechanism at the introductory side of the platen which facilitates the application of the invention thereto.

Therefore, the worksheets are creased, according to the present invention, by means mounted on the guiding and separating frame 24 of the machine. This frame comprises side plates 24a held together by a suitable tie bar 25, and confined between the side plates 24a are the rollers 15 over which the strips 14 pass in being led to the platen. For the purpose of separating the worksheets 14 and 14a as they approach the platen

16 and also to place on the worksheets a predetermined drag or tension, a group of tensioning and separating plates 26 are mounted on the guide rod, see Figs. 1 and 2. These plates lie one above the other and are pivotally supported by the rod 15 in staggered relation rearwardly from the lower tension plate to the upper one. The plates 26 are pressed downwardly to firmly engage the worksheets 14 and 14a which pass separately between them by a bar 27 carried by the top plate 28 of the manifolding machine. The top plate 28 is pivoted at 20 so that it may be swung upwardly to give access to the separating and tensioning frame 24-25, for the purpose of allowing the operator to thread the worksheets around the guide rollers 15 and between the plates 26, and when held in place by gravity or otherwise causes the bar 24 to bear downwardly on the plates 26. Preferably, there are two sets of plates 26 as shown in the drawings.

The present invention utilizes the two lowermost plates designated 26a of each set of plates 26 to produce a crease 30 in the record sheet 14a (Fig. 2) and for this purpose the two lowermost plates 26 are provided with embossed portions 31 lying directly above each other and preferably directly above a groove 32 in the platen 16, see Figs. 2 and 3, when in operating position. Hence, when the worksheets 14 and 14a are drawn by the feed mechanism comprising the rollers 16 and 17, the record sheet 14a is forced downwardly at its zone in the immediate vicinity of the embossings 31 and a substantially V-shaped crease is produced in the record sheet 14a, the pressure on the plates 26 produced by the member 27 on the top plates 28 causing the record sheets 14a to follow the contour of the embossings 31 in the two lower plates 26a.

It is not essential that the platen 16 be grooved to receive the lower embossed plate 26, but by having it so grooved lateral movement of the embossed plates 26a is provided and hence the creases 30 in the record sheets 14a will be straight.

It should also be noted that if the platen 16 were provided with a groove, the lowermost embossed plate 26a might be discarded and yet the machine would work fairly satisfactorily, for in such case the then lowest plate 26a would force the record copy 14a into the groove of the platen. However, by providing the lower plate 26a, the span between the first guide rod 15 and the platen is bridged and all danger of the worksheet dropping down in this gap is avoided. Moreover, the separator plates 26a may be shaped with more facility and more accuracy than the plate could be grooved. As herein disclosed, it is unnecessary to have the groove 22 in the platen accurately 130

formed so long as it is sufficient to prevent lateral movement of the embossed separator plates 26a.

When fed onto the record holding tray 21, the longitudinally creased sheets 14a are substantially flat, for the creases 30 are not extremely deep, being only sufficient to stiffen the paper longitudinally and prevent its curling. The creases 30 in the record strip 14a have another advantage and that is to assist in alining the sheets 14a laterally in the record pack. This is due to the fact that the creases 30 in the superposed record sheets 14a fit into each other and vibrations of the record support 21 cause them to be jogged into place.

From the above, it should be understood that the invention not only embraces the idea of creasing or otherwise changing the record copy so as to avoid its tendency to curl, but also embraces the idea of having the record copy previously creased or stiffened longitudinally for the same or an analogous purpose.

Variations and modifications may be made within the scope of this invention and portions of the improvements may be used without others.

Having thus described the invention, what is claimed as new and for which it is desired to obtain Letters-Patent, is:—

1. In a machine of the character described having a platen over which worksheets are fed and guide mechanism for introducing said worksheets to the platen, means cooperating with said guide mechanism for producing a crease in one of said worksheets to stiffen and prevent curling thereof.

2. In a machine of the character described having a platen over which worksheets are fed and guide mechanism for introducing said worksheets to the platen, means cooperating with said guide mechanism for producing a stiffening longitudinal crease in one of said worksheets as the same passes to the platen.

3. In a machine of the character described having a platen over which worksheets are fed, means for separating and guiding the worksheets as they are introduced to the platen said means including means for producing in one of said worksheets a longitudinal stiffening crease.

4. In a machine of the character described having a platen over which worksheets are fed, means for separating and guiding the worksheets as they are introduced to the platen comprising flat plates between which the worksheets are drawn, at least one of said plates being provided with a rib engaging one of said worksheets to produce therein a longitudinal stiffening crease.

5. In a machine of the character described having a platen over which worksheets are fed, means for separating and guiding the

worksheets as they are introduced to the platen comprising flat plates between which the worksheets are drawn, two of said flat plates being provided with nested ribs for producing in one of said worksheets a longitudinal stiffening crease.

6. In a machine of the character described having a platen over which worksheets are fed, means for separating and guiding the worksheets as they are introduced to the platen comprising flat plates between which the worksheets are drawn, at least one of said plates being provided with a groove into which the worksheet is pressed to produce therein a longitudinal stiffening crease, and said platen being provided with a complementary groove into which the grooved portion of said plates extends to prevent lateral movement of said plate.

7. A manifolding machine having a platen for supporting a worksheet in position to be written upon, a record compartment into which the worksheet passes after having been written upon, and means located at the introductory side of the platen for producing a longitudinal crease in the worksheet to stiffen the same as the sheet is drawn from the platen.

8. A manifolding machine having a supply compartment for worksheets, a platen for supporting worksheets in position to be written upon, a record compartment into which the worksheet passes after having been written upon, and means engaging one of the worksheets as the latter advance toward the platen from said supply compartment for producing in the worksheet a longitudinally extending crease to stiffen the same.

9. A manifolding machine having a platen for supporting worksheets in position to be written upon, a record compartment into which the worksheet passes after having been written upon, and means located at one end of the platen for producing a longitudinal crease in one of the worksheets to stiffen the same as the worksheets are drawn from the platen.

Signed at Hoboken, in the county of Hudson, and State of New Jersey, this 5th day of November, 1926.
